TOY GUN

Louis Marx, New York, N. Y.

Application September 23, 1950, Serial No. 12,327

Term of patent 7 years

(Cl. D34—15)

To all whom it may concern:

Be it known that I, Louis Marx, a citizen of the United States and a resident of the city, county, and State of New York, have invented a new, original, and ornamental Design for a Toy Gun, of which the following is a specification, reference being had to the accompanying drawing forming a part thereof, wherein:

Fig. 1 is a top plan view of a toy gun, showing my new design;

Fig. 2 is a bottom plan view thereof;

Fig. 3 is a front elevational view thereof;

Fig. 4 is a rear elevational view thereof; and

Fig. 5 is a side elevational view thereof.

I claim:

The ornamental design for a toy gun, substantially as shown.

LOUIS MARX.
